G. BEIGEL.

Stereoscopic Apparatus.

No. 70,391.

Patented Nov. 5, 1867.

Fig. 2.

United States Patent Office.

GEORG BEIGEL, OF NEW YORK, N. Y.

Letters Patent No. 70,391, dated November 5, 1867.

IMPROVEMENT IN STEREOSCOPIC APPARATUS.

The Schedule referred to in these Letters Patent and making part of the same.

TO ALL WHOM IT MAY CONCERN:

Be it known that I, GEORG BEIGEL, of the city of New York, 25 Delancey street, in the county and State of New York, have invented a new and improved Stereoscopic Apparatus; and I do hereby declare that the following is a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is a sectional plan or top view of the same.

Similar letters indicate corresponding parts.

This invention relates to a stereoscopic apparatus which is so arranged that a number of pictures can be introduced simultaneously all in a "pack," and the necessity of securing each picture in a separate picture-holder is avoided. The pictures thus introduced are carried down singly before an opening in the case opposite the eye-glasses by means of a feed-screw and separating-screw, and after a picture has been exhibited it is dropped down in the lower part of the case, where all the pictures arrange themselves in a "pack," so that they can be readily removed whenever it may be desired.

A represents a case made of wood or any other suitable material, of such a size that it is capable of covering up and protecting the mechanism for moving and separating the pictures. These pictures are placed in a "pack" on the platform B, where they are retained in an inclined position by the slide C, (see fig. 1.) This slide moves back and forth on suitable guides, motion being imparted to it by a worm-screw, D, which is situated within the platform B, in such a position that the edges of the threads project above the surface of said platform. A revolving motion is imparted to said screw by means of a handle or key, which is inserted through a hole in the side of the case, and which fits on the end of a shaft or arbor that connects with said feed-screw by a worm and worm-wheel, or in any other suitable manner. The feed-screw D imparts motion to the slide C, from the bottom of which projects a tooth, a, down into the threads of the screw. This tooth is rigidly connected to a bar, a', which is pivoted to a lug, b, that is secured to the rear wall of the slide C, and a spring, c, has a tendency to raise the same up out of contact with the threads of the feed-screw. When the tooth is depressed, however, it is locked down by a swinging bolt, d, which has its fulcrum on a pivot, d', and which is provided with a notch or shoulder that catches over the edge of the tooth a, or bar a'. The upper end of the bolt d catches in a tappet-rod, e, which extends beyond the ends of the slide, and if said slide has reached the forward end of its stroke, the ends of the tappet-rod come in contact with projections e in the interior of the case, and the bolt becomes disengaged from the tooth or bar, so as to allow said tooth to rise out of contact with the threads of the feed-screw. When the slide arrives at the backward end of its stroke the pin f comes in contact with the inner rear surface of the case, and by its action the elbow-lever f' is turned on its pivot, and the bar a', together with the tooth a, is depressed. Between the lever f' and bar a' a spring, f'', is interposed so as to allow the tooth to give if it should not be exactly opposite to a cavity on the feed-screw, and to accommodate itself automatically as the work progresses. As the slide is propelled by the feed-screw in the direction of the arrow marked near it in fig. 1, the pictures are gradually forced out over the apron E, and one picture after the other comes in contact with the separating-screw F. This screw is geared together with the feed-screw by cog-wheels g h, so that it revolves six times, more or less, as fast as the feed-screw, in order to prevent any accumulation or chocking of the pictures, and it is provided with a series of spiral steps, some of which, and particularly those towards the end of the separating-screw, are so narrow that they are certain to afford room for only one picture. By these spiral steps the pictures are separated from each other, and the first picture in the pack on reaching the last step drops down over the segmental guide-ways G, being caught by the trap H. This trap is situated at the bottom edge of an aperture, I, in the case, and the picture arranges itself on the inside of this aperture in an upright position opposite the eye-glasses J. These eye-glasses are attached to a flap, K, which connects to the case A by means of hinges, so that it can be turned up or down, and the eye-glasses themselves are so arranged that they can be folded down upon the flap K, or that they can be held in the proper position for looking at the pictures. This purpose is effected by securing the eye-glasses in a hinged head, L, to which is attached a hinged T-shaped brace, M, and the cross-bar of this T-shaped brace is also hinged, so that the whole device can be folded together when the eye-glasses are not used. When the

eye-glasses are put up for use, the brace M bears against a lip, i, as shown in the drawing, and this brace also forms the diaphragm between the eye-glasses. The trap H is hung on pivots k, secured in the sides of the case A, and it is so loaded that when it is left to follow its inherent gravity it will turn down and cause the picture to drop down into the lower part of the case. From the trap extends an arm, l, which bears against a pin, m, secured in the lever n, which is subjected to the action of a spring, o, having a tendency to keep the same in the position which it occupies in fig. 1. From the upper end of the lever n projects a handle or button, and if said handle is carried in the direction of the arrow, marked near it in fig. 1, the pin m is thrown off from the arm l, and the trap H is free to follow its gravity and to tilt down. After the picture delivered by the feed-screw and separator to the trap has been viewed, the trap is tilted and the picture is caused to drop down into the lower part of the box, and as the handle is released, the trap is thrown back to its original position, and a finger, N, strikes the picture and throws it back against the lower slide O. The finger N projects from an arm, p, which connects with the lever n by a lever, q, and link, r, or in any other suitable manner, so that it is compelled to move with the same. From the lower slide O extends a cord or band, s', to a drum, s, which is mounted on an arbor, P, which connects by a cord or band, t, with the upper slide C, so that the lower slide is drawn back as the upper slide advances by the action of the feed-screw. The diameter of the drum s, however, is larger than that part of the arbor P on which the cord t winds, so that the lower slide moves somewhat faster than the upper one, and sufficient room is obtained for the pictures as the same drop down into the lower part of the case. After the whole number of pictures have been viewed and caused to accumulate in the lower part of the case, a door in the side of said case is opened and the pack of pictures is removed without loss of time, and as the upper slide reaches the forward end of its stroke the tappet-rod e strikes the projections e', and the tooth a is thrown out of gear with the feed-screw, leaving the upper slide free to be moved back on its guides. This backward motion is produced by a key which is inserted through a hole in the lower forward end of the case, and which acts on a roller, Q, from which one or more bands u extend to the lower slide. By turning this roller in the direction of the arrow marked on it in fig. 1, the lower slide O is drawn forward, and at the same time, by the action of the cords s' t, the upper slide C is drawn back, and as it arrives at the back end of its stroke the stop f strikes the case, and the tooth a is again thrown in gear with the feed-screw, ready for a new operation.

If desired, my apparatus can also be used for transparent pictures by opening a door in the rear of the case. The operation of feeding these pictures is the same as that of feeding opaque pictures, and in order to prevent injurious shocks the trap H and the lower part of the case may be cushioned.

What I claim as new, and desire to secure by Letters Patent, is—

1. Introducing the pictures into the stereoscopic apparatus in "packs" or quantities, instead of singly or in pairs, as heretofore, substantially as and for the purposes described.
2. The feed-screw D and slide C for propelling the "pack" of pictures, substantially as set forth.
3. The separating-screw F, provided with spiral steps, substantially as and for the purpose described.
4. The tappet-rod e, bolt d, and tooth a, in combination with the projections e', slide C, and feed-screw D, substantially as and for the purpose set forth.
5. The stop f, in combination with the tooth a, slide C, feed-screw D, and case A, constructed and operating substantially as and for the purpose described.
6. The trap H, in combination with the feeding and separating mechanism, constructed and operating substantially as and for the purpose set forth.
7. The folding flap K, hinged T-shaped brace M, and hinged head L, in combination with the eye-glasses J and case A, constructed and operating substantially as and for the purpose described.
8. The oscillating finger N, in combination with the trap H, and with the feeding and separating mechanism, constructed and operating substantially as and for the purpose set forth.
9. The lower slide O, in combination with the folding and separating mechanism, constructed and operating substantially as and for the purpose described.
10. The method, herein described, of collecting the pictures in the lower part of the case after they have been viewed, so that they can be removed in quantities or "packs," as set forth.
11. Giving to the lower slide O a faster motion than to the feed-slide C, substantially as and for the purpose described.
12. The winding mechanism Q, in combination with the slides O C and cords s' t, constructed and operating substantially as and for the purpose set forth.
